UNITED STATES PATENT OFFICE.

WILLIAM H. HOOPER, OF LYNN, MASSACHUSETTS, ASSIGNOR TO MANUFACTURERS MACHINE COMPANY, OF MONTCLAIR, NEW JERSEY, A NEW JERSEY CORPORATION.

METHOD OF ASSEMBLING SHOE UPPERS AND SOLES.

No. 861,180.

Specification of Letters Patent.

Patented July 23, 1907.

Original application filed January 16, 1906, Serial No. 296,322. Divided and this application filed February 13, 1907.
Serial No. 357,173.

To all whom it may concern:

Be it known that I, WILLIAM H. HOOPER, a citizen of the United States, residing at Lynn, in the county of Essex and State of Massachusetts, have invented an 5 Improvement in Methods of Assembling Shoe Uppers and Soles, of which the following description, in connection with the accompanying drawings, is a specification, like letters on the drawings representing like parts.

10 This invention is a contribution to the art of bottoming boots or shoes, and relates more particularly to that stage of the bottoming operation at which sole leather is initially assembled with an upper.

In order that the purpose of the invention may be 15 clearly appreciated, it is expedient to explain, by way of illustration, certain methods which have been employed heretofore in assembling sole leather with uppers.

20 In bottoming operations as they have been most commonly practiced commercially, the material for the sole has been presented initially to the upper in one or the other of two forms, either as a previously shaped blank which has been die-cut or otherwise formed in substantially the shape it is desired to have 25 for the finished shoe; or else in the form of a block sole which is simply a piece of sole leather not definitely shaped but merely cut to a size convenient to be handled. The shape of a block sole may in some cases approximate, more or less nearly, the shape which the 30 finished sole is desired to have; but it is characterized by the fact that it presents at its edge considerable superfluous material which must be removed in order to produce the final desired sole shape. A sole blank die-cut or otherwise formed may need to be trimmed 35 somewhat after it is attached to the shoe but such trimming has no reference to the removal of surplus material and is intended generally to smooth up the sole edge and to erase such scars or the like as may have been received. Thus the trimming of a sole blank 40 partakes of the character of a finishing operation that is to say an operation directed to the improvement of the appearance of a shoe; while the cutting away of superfluous stock of a block sole is a shaping operation which is commonly called "rough rounding."

45 Whatever the form in which the sole leather is presented to the upper—whether it be a block sole or a sole blank—it is important that the operator adjust the sole leather properly with relation to the upper. This is usually done by placing the sole leather on the bottom of an inverted last bearing the upper; shifting the sole leather laterally and longitudinally on the last until it reaches its desired relation to the last and upper; and thereupon fastening the sole leather in adjusted 50 position, as by means of tacks driven through the sole

into the last. In placing the sole leather on the bottom of the inverted last the upper is nearly if not quite hidden from the sight of the operator who must therefore effect his adjustment blindly and by his sense of touch alone, or if the sole leather be placed upon the lasted upper while in upright position a like difficulty 55 is experienced. Frequently he is required to feel entirely around the last to insure that the sole leather shall extend sufficiently on all sides. In general, this is equally true whether he is employing a block sole or a sole blank. However, the fact that a block sole has 60 a greater area than is intended for the finished sole permits the block sole to be assembled with the upper by a more or less crude and approximate adjustment since slight mistakes may be corrected in the rough rounding; but a sole blank, already having substantially its 65 final shape, must be adjusted on the upper with extreme care and accuracy since, once adjusted, the sole blank is permanently secured to the upper, and if the adjustment be faulty the fault is practically incurable by trimming or the like, and the entire shoe must be 70 discarded. Comparatively then, the adjustment of a sole blank involves much greater difficulty and demands greater skill on the part of the operator, than does the adjustment of a block sole.

Such circumstances as those just pointed out have 75 tended to deter manufacturers from using sole blanks instead of block soles, although for many reasons the former are greatly preferred in some classes of work. For example, sole blanks for a given size and style of shoe are usually formed in considerable numbers 80 from a single die or a single pattern, and consequently they preserve throughout a succession of shoes a definite uniform style; whereas block soles are shaped, by the rough rounding operation, each with reference to the contour of its particular upper, and these contours (because of defects in lasting, variations in thickness of upper leather and the like) may exhibit 85 various undulations all of which affect the rough rounded outline of the sole with the result that even in a single pair of shoes the soles may be of different shapes. 90 While such differences in shape may not be very great they are none the less important, especially in shoes of high grade. Moreover certain operations following the attachment of the sole leather, such as channeling for the outsole stitching, are sometimes desired to be 95 gaged from the sole edge; and any imperfections in said edge, such as may result from rough rounding, will be communicated to the channel and consequently to the outsole so that the latter, often a conspicuous element of the shoe, appears in a wavering or otherwise 100 imperfect line and therefore detracts from the appearance of the shoe.

Not the least advantage arising from the use of sole

blanks, resides in the elimination of the sole rounding operation which is perhaps as exacting of the operator's skill and care as any operation in the manufacture of shoes. In spite of the advantages just exemplified, as supplied by sole blanks, the difficulties attending their proper adjustment to an upper have led to the more general use of block soles.

It is an important object of this invention to facilitate the adjustment of sole leather to uppers to the end that block soles and sole blanks may be adjusted with equal rapidity and with desired accuracy by a comparatively unskilled operator. It follows then that the practice of this invention, if so desired, admits of the use of sole blanks exclusively with all the attendant advantages while at the same time preserving the facility of adjustment which heretofore has recommended the use of block soles.

Certain features of the invention will be described herein, for purposes of illustration, as practiced in part by a machine disclosed in a copending application Serial No. 296,322, filed January 16, 1906, of which this is a division; but nothing herein contained is to be construed as limiting the scope of this invention to use in connection with said machine.

Also a method embodying the invention will be described herein as employed in assembling a sole blank with a lasted and welted upper mounted on a last.

Obviously, however, the scope of the invention is not to be limited to the exact characteristics of the specific form of sole leather and upper described.

In the accompanying drawings; Figure 1, is a diagrammatic bottom plan view of part of a welted upper showing the welt marked in a manner convenient for the practice of a method embodying this invention; Fig. 2, is a side elevation of a machine capable of marking a welt in the manner illustrated in Fig. 1; Figs. 3 and 4, are respectively a plan view and a front elevation of the machine shown in Fig. 2; Fig. 5, is a transverse section of a form of marking tool, on the line 5—5 of Fig. 2.

The welt *a* shown in Fig. 1 is of greater width than it is desired to have on the finished shoe, it being preferable to trim down a welt which is too wide, rather than to run the risk of having it so narrow as not to register with the edge of the finished sole. This use of wide welts is an expedient very generally adopted and consequently the welt edge should not be used by the operator as a guide in adjusting the sole leather, since thereby a sole might be improperly positioned. Moreover imperfections in inseam sewing, or improper variations in an insole channel might distort a welt edge from its intended outline. In practice therefore, a welt edge is an unsafe gage for adjusting sole leather to a welted upper.

The specific method, to be described as embodying this invention contemplates making on the welt one or more marks to which the edge of a sole blank may be referred for purposes of adjustment, and as pointed out it is impracticable to determine the position of such a mark with relation to the welt edge. Accordingly it is preferred to locate the marks by reference to the general contour of the upper as by measuring from the bulge of the upper on the last, transversely of the welt and locating the mark at the desired distance from the last so measured. This preference is emphasized by

the fact that the style of a shoe, its distinctive appearance, depends largely upon the relations existing between general contour of the upper and sole; that is to say, one of the most conspicuous elements in the appearance of a shoe when worn, is the greater or less extent to which the sole projects beyond the outline of the upper. Hence, by marking a welt with reference to an upper and at a predetermined distance therefrom, and adjusting a sole to the upper with relation to said mark, a distinctive style can thereby be determined for the shoe. By varying the distance of the mark from the upper different styles of shoes may be determined.

In making some styles of shoes it is desirable that certain parts of a sole extend a greater distance beyond the upper than others—for example the toe of the sole may extend a greater distance than the lateral instep portions, or vice versa. In such cases this invention may be practiced conveniently by locating a mark on the welt at one distance from the toe of the upper and another mark at a different distance from the instep portion of the upper; and adjusting the sole blank by reference to said marks respectively.

The marks may be of any practicable character to suit their intended purpose. It is preferable, however, to use marks of the sort shown in Fig. 1. Each mark *b* consists of a line extending along substantially the outline intended for the finished sole; and as shown in Fig. 1 there are three of such marks (although this number is, of course, not indispensable) one mark being positioned proximate the toe portion to assist in adjusting the sole lengthwise of the upper, and one or more marks being positioned at a side of the upper to assist in the lateral adjustment of the sole. Each mark *b* is supplied in the specific illustration by cutting a rectangular notch in the edge of the welt, the inner side of the notch constituting the desired demarcation to which the sole adjustment is referred. A notch of this shape is especially convenient in that it permits the operator to place some positioning element, such as his finger or a tool, in the notch with a face of the positioning element abutting against the inner edge of the notch; and then to adjust the sole by causing it to abut against the positioning element in such manner that the sole edge will register exactly, or as nearly as may be desired, with the mark. Thus, for example, an operator might place the sole blank upon the welt shown in Fig. 1, place certain of his fingers in the notches and then shift the sole until its toe end touches the finger at the toe notch and the forepart edge touches his fingers at the lateral notches. It is of course, a comparatively simple matter to effect by touch alone an adjustment of two parts which are desired exactly to register and the operator by feeling the notch edges and sole can tell whether or not they register properly and conduct his adjustment accordingly. The specific arrangement illustrated in Fig. 1, however, supplies the additional advantage of permitting the operator to observe the adjustment since the sole edge is intended to register with, but not to extend beyond, the marks *bb*. It is true moreover, with this arrangement, that the operator can adjust a sole into registry with the mark *b* by sight alone unaided by his sense of touch.

The machine of the aforesaid co-pending application, which is also shown in the present drawings, is capable of making such marks as are shown in Fig. 1, that is to

say, the specific machine is arranged for cutting rectangular notches in the edges of a welt or the like.

In using the machine the bulge of the upper over the last adjacent the welt is placed against an edge gage *c* (in the manner indicated by dotted lines in Fig. 2) with the welt overlying a marking bed *d*. Thereupon a vertically movable marking tool in this instance a knife *e*—is depressed against the marking bed *d* to mark the welt. Preferably the marking tool *e* is fixed 10 against lateral movement; and in order that it shall mark a welt at different distances from the contour of the upper the edge gage *c* is made horizontally adjustable so as to vary the horizontal distances between the marking position of the tool and the location of the 15 upper as determined by the edge gage. The edge gage *c* comprises a plate which is movable horizontally on the table *f* of the machine; and it is so moved by means of an edge gage adjusting lever *g* pivoted to the bed *f* at *h* and connected to the gage plate *c* through the 20 rod *i* secured to said plate and carrying at its end collars which engage between them the bifurcated end of the edge gage adjusting lever *g*. Also connected to the gage plate *c*, by means of a pin and slot connection shown in Fig. 3, is an indicator lever *j* pivoted to the 25 machine bed at *k* and having its outer extremity in the form of a pointer to coöperate with an indicator scale *l* which may be graduated according to any desired system of styles or sizes. To facilitate the adjustment of the edge gage *c* adjustable stops *m* *n* are provided by 30 which the indicator lever *j* will be arrested when the adjusting lever is moved. These stops may conveniently have the form of removable pegs; and a series of peg holes *o* may be provided for different adjustments of one of the stops; while a slot *p* may be provided for 5 the adjustment of the other peg which may conveniently be provided with a clamp-nut to hold it in position in the slot *p*. The specific peg *n* may serve to hold the indicator lever in contact with the other stop *m*; or if preferred, the two stops may be spaced apart 10 so that only one of them at a time will engage the indicator lever *j*, whereby the operator may be permitted by moving the adjusting lever *g* to shift the edge gage in and out between the limits determined by the two pegs *m* and *n*.

For the purpose of making the rectangular notch in the welt as shown in Fig. 1, the marking tool *e* has substantially the cross section shown in Fig. 5. The mark-

ing tool *e* is carried at the lower extremity of a plunger *q* normally upheld by a spring *r*. The tool *e* is depressed to mark against the marking bed *d* by means 50 of a lever *s* and treadle *t*.

In addition to the edge gage *c* it is considered expedient to employ another gage *u* against which the bottom of the last, or the insole, if there be one, or some other part, may be held to assist in determining the 55 horizontal relation of the upper to the marking tool.

Occasion has arisen in the foregoing discussion to use the words "upper" and "welt" to indicate distinct parts of the shoe, but as a matter of fact, the welt is for the purpose of the bottoming operation substantially an integral part of the upper. Accordingly in the sub-joined claims, where the context permits, the words "upper portion of a shoe" may be understood if necessary, to include a welt or any equivalent thereof, such for example, as the out turned edge of an upper 65 for a stitch-down shoe.

This invention supplies a highly meritorious contribution to the art to which it pertains and it is thought to be a pioneer invention, in that, as to certain features, it contemplates that sole leather and an upper 70 shall be assembled and adjusted with reference to a definitely placed demarcation on one or the other of them.

I claim as my invention:—

1. A method of assembling sole leather and an upper 75 portion of a shoe which consists in notching one of them, placing a positioning element in the notch, and adjusting them by reference to said positioning element.

2. The method of assembling a sole portion and an upper portion of a shoe, which consists in notching one of 80 them at the toe and at the side, and then adjusting the other relatively thereto with reference to the said notches.

3. The method of laying outsoles on welted boots and shoes which consists in marking the welt at its under side in definite position relative to the location of the upper, 85 and laying the sole to said marks at the under side to define the position of the sole predeterminedly with relation to the upper when the welt is trimmed away.

4. The method of laying outsoles on welted boots and shoes which consists in notching the said welt with respect 90 to a selected outline of the shoe, and positioning the outsole on the shoe with reference to said notch.

In testimony whereof, I have signed my name to this specification, in the presence of two subscribing witnesses.

WILLIAM H. HOOPER.
